UNITED STATES PATENT OFFICE.

ISIDOR KITSEE, OF PHILADELPHIA, PENNSYLVANIA.

ELECTRIC TELEGRAPHY.

SPECIFICATION forming part of Letters Patent No. 793,037, dated June 20, 1905.

Application filed February 4, 1905. Serial No. 244,189.

To all whom it may concern:

Be it known that I, ISIDOR KITSEE, of the city and county of Philadelphia, State of Pennsylvania, have invented certain new and useful Improvements in Electric Telegraphy, 5 of which the following is a specification.

My invention relates to an improvement in electric telegraphy, and has more special reference to the symbols of telegraphic alphabets.

The universal telegraphic code—Morse alphabet—consists of dots and dashes grouped differently for different letters. On land lines these dots and dashes are produced 15 through a shorter or longer contact of the transmitting-key with a source of current of one polarity. On submarine cables these dots and dashes are symbolized, one by an impulse of one polarity and the other by an 20 impulse of opposite polarity. In the telegraphing with alternating currents the dot is symbolized by a few complete cycles and the dash is differentiated from the dot by a greater number of cycles. In some methods 25 part of the cycles are depressed or combined with currents of higher intensity. I have found that on lines with great capacity it is 30 advantageous to telegraph with true reversals—that is, with impulses always of substantially the same duration and intensity, 35 but always of opposite polarity. To symbolize the dots and dashes in such a system, the only recourse left is to change the unit of time lapsing between the different impulses. In 40 stead of differentiating the dot from the dash by a shorter or longer depression of the key, as in land lines, or by changing the polarity, as in the cable, I symbolize the dot by one short depression of the key, allowing a whole 45 unit of space to pass before a second depression, and I symbolize a dash by two depressions of the key in quick succession, allowing only a part of the time to lapse between these 50 two depressions. The second depression of the dash transmits a current of a polarity opposite to the polarity of the first depression. A dash therefore in my system will consist at 55 the receiving-station, if recorded, of two dots in close proximity to each other, each dot be-

ing the resultant effect of a depression of a 50 key connected to a source of current of a different polarity.

In cable telegraphy the alphabet mostly employed is not the so-called "American Morse," but it is the Continental Morse, the 55 difference in the two systems laying therein that in the Continental Morse a greater number of dashes are employed, so that the letters do not need to have so many groupings of symbol elements. In my system it is best 60 to employ the alphabet known as the "American Morse."

In contradistinction to all systems so far employed my invention consists therein that the symbol which is generally expressed by a 65 dash in the Morse alphabet is expressed in my method by two symbol elements following at short intervals and each symbol element of a different polarity, and that a dot is symbolized by one impulse, the polarity of 70 same not coming into consideration so long as the same is opposite to the polarity of the impulse preceding.

In the drawing I have illustrated both symbols according to my improved method and 75 in contradistinction thereto the Morse symbols now used.

Having now described my invention, what I claim as new, and desire to secure by Letters Patent, is—

1. In a telegraphic alphabet a symbol consisting of two elements, each element representing a dot, both elements in close proximity to each other, each of said elements of an opposite polarity.

2. A telegraphic alphabet comprising two symbols, one symbol consisting of one element, the second symbol consisting of two elements in close proximity to each other, these two elements being of opposite polarity 90 to each other.

3. A telegraphic code comprising different grouping of two symbols, one symbol consisting of one element and the second symbol consisting of two elements in close proximity to 95 each other, each of these elements of a polarity opposite to the other.

4. A telegraphic Morse alphabet in which

the dash is symbolized by two elements in close proximity but of opposite polarity to each other.

5. A telegraphic alphabet comprising two different characters, one character symbolized by a dot of a positive or negative polarity in accordance with the polarity of the impulse preceding and one character symbolized by two dots in close proximity but of opposite polarity to each other.

6. A telegraphic alphabet comprising two characters, one character consisting of one

element followed by a space unit and the second character consisting of two elements separated by part of a space unit, and followed by a whole space unit. 15

In testimony whereof I hereby sign my name, in the presence of two subscribing witnesses, this 2d day of February, A. D. 1905.

ISIDOR KITSEE.
